UNITED STATES PATENT OFFICE.

JACK G. METROPOL, OF SUMTER, SOUTH CAROLINA.

DESIGN FOR A BOTTLE.

Application filed January 2, 1925. Serial No. 11,858. Term of patent 14 years.

To all whom it may concern:

Be it known that I, JACK G. METROPOL, a citizen of Greece, residing at Sumter, in the county of Sumter and State of South Carolina, have invented a new, original, and ornamental Design for Bottles, of which the following is a specification, reference being had to the accompanying drawings, forming a part hereof.

I claim:

The ornamental design for a bottle as shown.

JACK G. METROPOL.
